TUNING INDICATOR FOR CARRIER-SIGNAL RECEIVERS

Robert T. Hintz, Woodhaven, N. Y., assignor to
Hazeltine Corporation, a corporation of Delaware

Application March 27, 1940, Serial No. 326,149

8 Claims. (Cl. 250—40)

The present invention relates to improved tuning indicators for carrier-signal receivers and, particularly, to tuning indicators of the cathode-ray tube type especially suitable for use in tunable frequency-modulated carrier-signal receivers.

Carrier-signal receivers conventionally are provided with an adjustable tuning means for tuning the receiver to a desired carrier signal which may comprise either conventional adjustable tuning elements or preselector tuning elements which may be selectively connected into the receiver circuit and a vernier tuning element to procure more precise tuning. Inasmuch as inaccurate tuning of the receiver frequently results in undesirable distortion of the received signal, the cause of which may not be recognized by the listener, it is further conventional to provide the receiver with a visual tuning indicator by which the receiver may be more precisely tuned to a desired carrier signal. The tuning indicators of the prior art have been devised in large part for amplitude-modulation carrier-signal receivers and generally have consisted of some device for indicating the magnitude of a unidirectional current or voltage derived from, and varying with, the signal-carrier energy of the signal translated by the receiver, which, in turn, varies in accordance with the accuracy of tuning of the receiver to a signal-carrier wave of constant frequency. The strength of the amplitude-modulated signals translated by the receiver, in general, is greatest when the receiver is accurately tuned to the desired signal-carrier wave and the indication of the tuning device is likewise a maximum or minimum under this condition of tuning.

In frequency-modulated carrier-signal receivers, however, amplitude variations of the translated signal are undesirable and are, in fact, deliberately suppressed by special limiter devices which reduce all signals to a substantially constant amplitude, generally that of the weakest carrier signal which the receiver can satisfactorily reproduce.

The tuned circuits of a frequency-modulation receiver generally have a fairly uniform response over a broad frequency band. Thus, even though the intensity variations of received signals are not reduced by limiter devices until the signals have been extensively amplified in the receiver, it is difficult with such broadly-tuned circuits to ascertain within a reasonable degree of accuracy the condition of tuning of the receiver to a received carrier signal where the tuning indica-

tion is derived from the signal energy appearing in the signal channel of the receiver at some point ahead of the limiter devices. While it is possible to provide a special signal-translating channel through which signal energy can be supplied to a tuning indicator of the prior art type, such special channel necessarily has relatively sharply-tuned circuits and it is difficult to maintain these circuits properly aligned with the tuned circuits of the receiver at the high carrier frequencies commonly used for frequency-modulation transmissions. This is especially true in regard to changes in the resonant frequency of the tuned circuits due to changes of humidity, temperature, and the like, and applies to a marked extent to the maintenance of the same resonant frequency between the sharply-tuned circuits of the indicator control channel and the tuned circuits of the frequency-detector system normally employed in a frequency-modulation receiver. The tuning indicator arrangements of the prior art, therefore, are not suitable for use in frequency-modulated carrier-signal receivers.

It is an object of the invention, therefore, to provide a new and improved tuning indicator which, while of general application, is especially suitable for use in frequency-modulation receivers and one which avoids one or more of the above-mentioned disadvantages of the prior art devices.

It is a further object of the invention to provide a tuning indicator which visually indicates by the relative position, size, and symmetry of two luminescent areas produced on the screen of a cathode-ray tube the degree and direction of mistuning of the receiver to a received carrier signal.

In accordance with one embodiment of the invention, a tuning indicator for a carrier-signal receiver including an adjustable tuning means comprises a cathode-ray tube, an input circuit adapted to have applied thereto a unidirectional control potential, the magnitude and polarity of which vary in accordance with the degree and direction, respectively, of mistuning of the receiver on either side of the received signal. The tuning indicator also includes means for deriving from the unidirectional potential two unidirectional control signals varying in accordance therewith in opposite senses, and means responsive to the control signals for deflecting the cathode ray of the tube to produce on the screen of the cathode-ray tube two luminous areas, the relative mean positions of which on the screen

visually indicate the degree and direction of the mistuning.

For a better understanding of the present invention, together with other and further objects thereof, reference is had to the following description taken in connection with the accompanying drawing, and its scope will be pointed out in the appended claims.

Referring now to the drawing, Fig. 1 is a circuit diagram, partly schematic, of a complete carrier-signal receiver embodying the invention; Fig. 2 illustrates the deflection patterns produced under various tuning conditions of the receiver upon the screen of the cathode-ray tuning indicator tube employed in the Fig. 1 embodiment; Fig. 3 is a circuit diagram of a modified form of the tuning indicator circuit of the invention; and Fig. 4 illustrates schematically a modified cathode-ray tube construction which may be employed with any of the forms of the invention shown in the several figures.

Referring now more particularly to Fig. 1, there is represented schematically a complete frequency-modulated carrier-signal receiver of a conventional design embodying the present invention in a preferred form. In general, the receiver includes a tunable radio-frequency amplifier 10 having its input circuit connected to an antenna system 11, 12, and having its output circuit connected to a tunable frequency changer or oscillator-modulator 13. Connected in cascade with the oscillator-modulator 13, in the order named, are an intermediate-frequency amplifier 14 of one or more stages, an amplitude limiter 15, a frequency detector and tuning indicator system 16, more fully described hereinafter, an audio-frequency amplifier 17 of one or more stages, and a sound reproducer 18.

It will be understood that the various units just described may, with the exception of the frequency detector and tuning indicator 16, be of a conventional construction and operation, the details of which are well known in the art, rendering further description thereof unnecessary. Considering briefly the operation of the receiver as a whole, and neglecting for the moment the operation of the frequency detector and tuning indicator 16 presently to be described, a desired frequency-modulated carrier signal is selected and amplified by the tunable radio-frequency amplifier 10, converted to a frequency-modulated intermediate-frequency carrier signal in the oscillator-modulator 13, amplified in the intermediate-frequency amplifier 14, limited to a predetermined substantially constant amplitude by the limiter 15, and detected by the frequency detector 16, thereby to derive the audio-frequency modulation components. The audio-frequency components are, in turn, amplified in the audio-frequency amplifier 17 and are reproduced by the sound reproducer 18 in a conventional manner.

Referring now more particularly to the portion of the system embodying the present invention, there is coupled to the amplitude limiter 15 a frequency detector and tuning indicator system 16. The system 16 comprises a frequency-responsive network 19, a pair of diode detectors 20, 21, and load resistors 22, 23 individual to the diodes 20, 21, respectively. The frequency-responsive network 19 comprises a primary tuned circuit including a condenser 24 and an inductor 25 inductively coupled to an inductor 26 of a secondary circuit tuned by a condenser 27. The primary tuned circuit 24, 25 and the secondary tuned circuit 26, 27 are tuned to the mean inter-

mediate frequency of the receiver. A condenser 28 is connected between the high signal potential terminal of the primary tuned circuit 24, 25 and the mid-point of the secondary inductor 26. The junction point of the resistors 22, 23 is connected to the mid-point of the secondary inductor 26 to complete the direct current path for the rectified currents of the diodes 20, 21. An intermediate-frequency by-pass condenser 30 is connected across the resistors 22, 23.

The tuning indicator of the invention comprises a cathode-ray tube 32 of the type having a pair of deflecting electrodes 33 and 34, each adapted and arranged to deflect in different directions a beam of electrons emitted by a cathode 35 and attracted to a fluorescent screen or anode 36. In a conventional tube of this type, the anode has a frusto-conical shape and the cathode is an elongated cylinder coaxially positioned with respect to the anode. The deflecting electrodes are generally rods of a diameter appreciably smaller than that of the cathode, the deflecting electrodes being positioned with their axes parallel to each other and to the axis of the cathode but spaced from the cathode on opposite sides thereof.

The circuit of deflecting electrode 33 is connected through a pair of tandem-connected direct current amplifiers 37 and 40 and through an audio-frequency filter, comprising a shunt condenser 46 and a series resistor 47, to the high-potential terminal of the resistors 22 and 23 in series. The deflection electrode 34 is similarly connected through a single direct current amplifier 41 and through the audio-frequency filter 46, 47 to the high-potential terminal of the resistors 22 and 23 in series. Operating current for the amplifiers 40 and 41 is supplied through load resistors 38 and 42, respectively, from a source of operating potential +B as indicated.

In considering the operation of the circuit just described, it will be seen that the frequency-responsive network 19 and frequency detector are, in general, similar to conventional frequency-discriminating networks utilized in automatic frequency control systems of the prior art and utilize the principle of rectifying separately the sum and difference of the voltages across the primary and secondary of a double-tuned circuit and combining differentially the rectified voltages so obtained to provide a unidirectional voltage the magnitude and polarity of which vary in accordance with the degree and direction, respectively, of mistuning of the receiver on either side of a received carrier signal.

Assume that the receiver is accurately tuned to a desired carrier signal so that the modulated intermediate-frequency carrier signal has a mean carrier frequency equal to the mean resonant frequency of the intermediate-frequency selectors of the receiver. Under these conditions, the unidirectional potentials produced across the resistors 22, 23 are of equal magnitude but of opposite polarity. The audio-frequency filter 46, 47 removes the audio-frequency modulation components from this unidirectional potential and there is, therefore, no potential supplied through the audio-frequency filter 46, 47 to the amplifiers 37, 41. The normal operating currents of these amplifiers cause a normal potential drop to appear across the load resistors 38 and 42, respectively, thereby biasing the deflecting electrodes 33 and 34 to their normal operating potentials. The particular types of vacuum tubes employed 75 in the amplifiers 40 and 41 and the particular

values of the resistors 33 and 32 are so chosen that the normal operating potentials of the deflecting electrodes are equal. Each of the deflecting electrodes 33 and 34 produces an individual "shadow angle" on the fluorescent anode 36, the size of which varies with the magnitude of the control signal applied to the respective electrodes. The resultant "shadow angles" produced by the deflection electrodes are, therefore, equal when the normal operating potentials of these electrodes are equal and the deflection pattern which appears on the screen of the cathode-ray tube is symmetrical, as illustrated by the pattern of Fig. 2a, wherein the shadow angles are represented by the dark areas A and B and the equal luminous areas are represented by the light portions C and D.

Now assume that the receiver is mistuned to one side of a received carrier signal. The modulated intermediate-frequency carrier signal appearing at the output of the limiter 15 has a mean carrier frequency different from that of the mean resonant frequency of the intermediate-frequency selectors of the receiver. The frequency-responsive network 18 now operates to supply a larger potential to one of the diodes 20, 21 than to the other and a unidirectional differential potential appears across the resistors 22, 23. In this event, there is supplied through the audio-frequency filter 46, 47 to the amplifiers 31, 41 a unidirectional potential the magnitude of which is dependent upon the degree of mistuning. This potential is reversed in polarity in amplifiers 31 and 41 and again reversed in polarity in amplifier 40 and the transconductances of the amplifiers and the circuit constants are so proportioned that equal and opposite variations in potential are developed across the load resistors 38 and 42. The unidirectional potential across resistors 22 and 23 is then utilized and there is thus derived therefrom two unidirectional control signals, the relative magnitudes of which vary in accordance with the degree and direction of mistuning of the receiver on either side of the received carrier signal. These control signals are applied to the deflecting electrodes 33 and 34 of the cathode-ray tube 32 to produce equal and opposite variations of their operating potential.

The unsymmetrical deflection pattern produced on the screen of cathode-ray tube 32, under these conditions, is shown in Fig. 2b. There is thus provided by the several shadow angles and luminous areas independent visual indications which indicate both the degree or magnitude and the direction of mistuning of the receiver from the desired carrier signal. It may be noted that the size of the illuminated areas C' and D' is determined by the action of both deflecting electrodes. However, the deflecting effect of either deflecting electrode is limited by the structural arrangement of the tube elements and generally is not the same for equal increases and decreases of operating potential applied to the deflecting electrodes. Therefore, even though the control signals applied to the deflecting electrodes 33 and 34 vary equally and oppositely so that their difference is a constant, the illuminated areas, which represent the difference between the shadow angles of the two deflecting electrodes, vary not only in mean position but also in size or relative areas.

From the foregoing, it is evident that mistuning of the receiver to the opposite side of the desired carrier signal to that previously assumed

causes a reversal of the polarity of the unidirectional potential across the resistors 22, 23 with the result that the control signals applied to the deflecting electrodes 33 and 34 have the sense 5 of their relative magnitudes correspondingly reversed to produce the unsymmetrical deflection pattern illustrated in Fig. 2c. This pattern visually indicates, by the relative positions and areas of the luminous areas C'' and D'', the degree to 10 which the receiver is mistuned from the received carrier signal and that the receiver is mistuned in a direction opposite to that which produced the tuning indication of Fig. 2b, the shadow angle B'' being smaller than the shadow angle 15 A''.

It is therefore apparent that in the arrangement of Fig. 1 the deflecting electrodes 33 and 34 constitute a pair of deflecting means for the cathode-ray tube 32, which pair is adapted and 20 arranged to produce a symmetrical or an unsymmetrical deflection pattern according to the relative magnitudes of the control signals applied to the deflecting means. The deflection pattern is symmetrical or unsymmetrical in accordance with the equality or inequality, respectively, of the two unidirectional control signals which are applied to the deflecting electrodes 33 and 34. The tuning indicator also includes an input circuit which comprises the audio filter 25 which is made up of the condenser 46 and the resistor 47. From the high potential side of the load resistors 22 and 23, this input circuit is adapted to have applied thereto a unidirectional potential, the magnitude and polarity of which 30 vary in accordance with the degree and direction, respectively, of the mistuning of the carrier-signal receiver on either side of the received signal. In addition, the tuning indicator comprises the amplifier 41 connected to one of the deflecting electrodes 34 and the second amplifier 37 coupled to the second deflecting electrode 33 of the cathode-ray tube 32 through the polarity-reversing amplifier 40. These amplifiers are therefore included in the means for utilizing the unidirectional potential to produce or derive 35 therefrom the two unidirectional control signals which vary in accordance therewith in opposite senses. Stating this somewhat differently, the amplifiers 37, 40 and 41 comprise means responsive to the unidirectional potential for deriving and applying to the deflecting means 33, 34 equal unidirectional control signals when the receiver is accurately tuned and unequal unidirectional signals when the receiver is mistuned on either 40 side of the received signal. The connections from the amplifiers 40 and 41 to the deflecting electrodes 33, 34 are thus included in a means 45 for applying to the deflecting means 33 and 34 the control signals for deflecting the cathode ray of the tube to produce a deflection pattern, the symmetry of which visually indicates the condition of tuning of the receiver to the received signal. The deflection pattern produced on the screen of the cathode-ray tube includes two luminous areas in which the relative areas and the mean positions visually indicate the degree and direction of mistuning.

A modified form of the invention is shown in Fig. 3, wherein elements corresponding to like elements of Fig. 1 are indicated by like reference characters. In this modification, a single pentode vacuum tube 48 is employed to provide both amplification and phase inversion of the unidirectional potential appearing across the diode load resistors 22, 23. The input electrodes

of the tube 48, comprising a suppressor electrode 49 and a cathode 50, are connected through the audio-frequency filter 46, 47 across the resistors 22, 23. The anode 51 and the screen 52 both serve as output electrodes, each being connected to one of the deflecting electrodes 33 and 34 of the cathode-ray tube 32. The output electrodes 51 and 52 are energized through resistors 53 and 54, respectively, from a source of operating potential +B as indicated. The resistors 53 and 54 have values such that equal potentials are supplied to the deflecting electrodes 33, 34 when the receiver is not receiving any carrier signal and the characteristics of tube 48 are such that control signals of equal and opposite values are developed across resistors 53 and 54 in response to a control potential applied to its suppressor grid. Such amplifying and phase-reversing circuit is disclosed and claimed in United States Letters Patent No. 1,997,665, granted April 16, 1935, upon the application of Harold A. Wheeler.

The operation of the arrangement of Fig. 3 is identical to that of Fig. 1, the amplifying and phase-reversing tube 48 performing the function of the amplifiers 37, 40, and 41 of Fig. 1.

While it has been stated that the deflecting electrodes 33, 34 of the cathode-ray tube 32 are usually positioned 180 degrees apart on opposite sides of the cathode 35, as indicated in Fig. 2, it will be evident that the deflecting electrodes 30 may be spaced a lesser angle than 180 degrees, as illustrated in Fig. 4. If this is done, care should be exercised in so positioning the deflecting electrodes with respect to the cathode and in so biasing these electrodes that the shadow angles A and B permit only a narrow luminous line M to appear between them, as indicated in Fig. 4a, under the condition of exact tuning of the receiver to a received carrier signal. The position of the line M for exact tuning of the receiver to a received carrier signal may be indicated by a fixed indicator 51. Detuning the receiver on one side of the received signal has the effect that a luminous line M', Fig. 4b, moves to one side of the indicator 51 to a degree depending upon the degree of mistuning of the receiver. Similarly, mistuning the receiver to the opposite side of the received signal shifts the luminous line M'', Fig. 4c, to the opposite side of the indicator 51, the extent of its movement varying in accordance with the degree of mistuning of the receiver. If desired, the lower half of the cathode-ray tube screen may be masked or denuded of fluorescent material to eliminate the luminous areas N, N', and N'', thereby leaving only the movement of the luminous line M to provide the visual tuning indication.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A tuning indicator for a carrier-signal receiver including an adjustable tuning means comprising, a cathode-ray tube, an input circuit adapted to have applied thereto a unidirectional control potential, the magnitude and polarity of which vary in accordance with the degree and direction, respectively, of mistuning of said receiver on either side of said received signal,

means for deriving from said unidirectional potential two unidirectional control signals varying in accordance therewith in opposite senses, and means responsive to said control signals for deflecting the cathode ray of said tube to produce on the screen of said cathode-ray tube two luminous areas, the relative mean positions of which on said screen visually indicate the degree and direction of said mistuning.

2. A tuning indicator for a carrier-signal receiver including an adjustable tuning means comprising, a cathode-ray tube, an input circuit adapted to have applied thereto a unidirectional control potential, the relative magnitude and polarity of which vary in accordance with the degree and direction, respectively, of mistuning of said receiver on either side of said received signal, means for deriving from said unidirectional potential two unidirectional control signals varying in accordance therewith in opposite senses, and means responsive to said control signals for deflecting the cathode ray of said tube to produce on the screen of said cathode-ray tube two luminous areas, the relative areas of which visually indicate the degree and direction of said mistuning.

3. A tuning indicator for a carrier-signal receiver including an adjustable tuning means comprising, a cathode-ray tube, an input circuit adapted to have applied thereto a unidirectional control potential, the relative magnitude and polarity of which vary in accordance with the degree and direction, respectively, of mistuning of said receiver on either side of said received signal, means for deriving from said unidirectional potential two unidirectional control signals varying in accordance therewith in opposite senses, and means responsive to said control signals for deflecting the cathode ray of said tube to produce on the screen of said cathode-ray tube two luminous areas, the relative areas and mean positions of which visually indicate the degree and direction of said mistuning.

4. A tuning indicator for a carrier-signal receiver including an adjustable tuning means comprising, a cathode-ray tube, an input circuit adapted to have applied thereto a unidirectional control potential, the magnitude and polarity of which vary with the degree and direction, respectively, of mistuning of said receiver on either side of said received signal, means for deriving from said unidirectional potential two unidirectional control signals the relative magnitudes of which vary in accordance with the degree and direction of said mistuning, and means responsive to said control signals for deflecting the cathode ray of said tube to produce on the screen of said cathode-ray tube two independent visual indications which indicate the degree and direction of said mistuning.

5. A tuning indicator for a carrier-signal receiver including an adjustable tuning means comprising, a cathode-ray tube, an input circuit adapted to have applied thereto a unidirectional control potential, the magnitude and polarity of which vary in accordance with the degree and direction, respectively, of the mistuning of said receiver on either side of said received signal, means for deriving from said unidirectional potential two unidirectional control signals the relative magnitudes of which vary in accordance with the degree and direction of said mistuning and means responsive to said control signals for deflecting the cathode ray of said tube to produce on the screen of said cathode-ray tube

luminous areas which visually indicate the degree and direction of said mistuning.

6. A tuning indicator for a carrier-signal receiver including an adjustable tuning means comprising, a cathode-ray tube, an input circuit adapted to have applied thereto a unidirectional potential, the magnitude and polarity of which vary in accordance with the degree and direction, respectively, of the mistuning of said receiver on either side of said received signal, means for utilizing said unidirectional potential to produce two unidirectional control signals the relative magnitudes of which vary with the magnitude of said unidirectional potential and the sense of the relative magnitudes of which varies with the polarity of said unidirectional potential, and means responsive to said control signals for deflecting the cathode ray of said tube to produce on the screen of said cathode-ray tube two luminous areas which visually indicate the degree and direction of said mistuning.

7. A tuning indicator for a carrier-signal receiver including an adjustable tuning means comprising, a cathode-ray tube, a pair of deflecting means for said cathode-ray tube adapted and arranged to produce a symmetrical or an unsymmetrical deflection pattern according to the relative magnitudes of control signals applied to said deflecting means, an input circuit adapted to have applied thereto a unidirectional potential, the magnitude and polarity of which vary in accordance with the degree and direction, re-

10 spectively, of the mistuning of said receiver on either side of said received signal, means for utilizing said unidirectional potential to produce two unidirectional control signals varying in accordance therewith in opposite senses, and means for applying to said deflecting means said control signals for deflecting the cathode ray of said tube to produce a deflection pattern, the symmetry of which visually indicates the condition of tuning of said receiver to said received signal.

15 8. A tuning indicator for a carrier-signal receiver including an adjustable tuning means comprising, a cathode-ray tube, a pair of deflecting means for said cathode-ray tube adapted and arranged to produce a symmetrical or an unsymmetrical deflection pattern according to the equality or inequality, respectively, of two unidirectional control signals applied to said deflecting means, an input circuit adapted to have applied thereto a unidirectional potential, the magnitude and polarity of which vary in accordance with the degree and direction, respectively, of the mistuning of said receiver on either side of said received signal, and means responsive to said unidirectional potential for deriving and applying to said deflecting means equal unidirectional control signals when said receiver accurately is tuned and unequal unidirectional control signals when said receiver is mistuned on either side of said received signal.
